AIR CONDITIONING APPARATUS

William H. Leinweber, Chicago, Ill.

Application March 1, 1935, Serial No. 8,837

5 Claims. (Cl. 261—11)

This invention relates to air conditioning apparatus.

It is an object of this invention to provide an improved air conditioning apparatus which is relatively simple and inexpensive in construction and efficient in use.

Another object of this invention is to provide an improved device for both cooling and humidifying the air supply to a room or building.

10 Other objects will appear hereinafter.

The invention consists in the novel combination and arrangement of parts to be hereinafter described and claimed.

The invention will be best understood by reference to the accompanying drawings, showing the preferred form of construction and in which:

Fig. 1 is a side elevational view of a preferred form of the new apparatus, with parts of the casings thereof broken away, to reveal the operating parts;

20 Fig. 2 is a vertical sectional view on line 2—2 in Fig. 1;

Fig. 3 is an end elevational view on line 3—3 in Fig. 2, showing the air delivery grille embodied in the new apparatus;

25 Fig. 4 is a top plan view with parts of the casings broken away to reveal the operating parts;

Fig. 5 is a fragmentary end elevational view, on line 5—5 in Fig. 4, showing one of the cooling units embodied in the new apparatus;

30 Fig. 6 is a fragmentary end elevational view, on line 6—6 in Fig. 4, showing the fluid pump embodied in the new apparatus; and

Fig. 7 is a sectional view on line 7—7 in Fig. 4, showing the humidifying unit embodied in the new apparatus.

A preferred form of the new air-conditioning apparatus is shown in the drawings, is therein generally indicated at 10, and comprises a casing 11 in which is arranged a tank 12 adapted to 40 contain a supply of ice or other refrigerant.

Arranged in the tank 12 is a cooling coil 13 and attached to this coil 13 at one end thereof is a pipe or conduit 14 in which is arranged a fluid force pump 15, which is driven by a motor 16.

45 Likewise operated by the motor 16 is an air blower 17, which is preferably of the type described and claimed in my co-pending application, Ser. No. 747,315; Patent 2,026,689, dated January 7, 1936, this blower 17 being arranged in a housing 18.

The housing 18 has an extension 19 at one side thereof, and arranged in this extension 19 of the blower housing 18 is a cooling coil 20, one end convolution of this cooling coil 20 being connected, by

way of a pipe 21, to the cooling coil 13 which is arranged in the cooling tank 12. Provided in the extension 19 of the blower housing 18 is a water chamber or compartment 34 which is provided with a water inlet 33 and likewise provided in the extension 19 of the blower housing 18 is a fresh air inlet or grille 35. This inlet or grille 35 opens into an air duct 36 which includes a portion 37 which is attached to the bottom wall of the casing 11, this portion 37 of the conduit 36 extending 10 parallel to the long axis of the casing 11 and having an open end 38 (Fig. 1).

Leading from the blower housing 18 is an air delivery duct 22, which opens at its upper end into the casing 11, and this casing 11 is provided at 15 one end with an air delivery grille 24 which is adapted to open into a room or building for supplying cooled and humidified air thereto. The casing 11 is provided with a hinged top 26 (Fig. 2).

Surrounding the air duct 22 at a point between 20 the blower 17 and the casing 11 is an humidifying device (Figs. 2 and 7) which includes a water jacket 32 which is provided with a water inlet 28.

Arranged in the water jacket 32 is a perforated drum 30 and arranged within this drum 30 is a 25 water-absorbent annular member 27, which may be made of fabric, felt, or any other suitable water-absorbent material; and arranged inwardly of the water-absorbent member 27 is a perforated drum 31 (Fig. 2).

30 Leading from one end convolution of the cooling coil 20 to the pump 15 is a pipe 33 in which is provided a suitable drain valve 40.

Operation

35 A supply of ice or other refrigerant may be inserted into the tank 12, by opening the hinged top 26 of the casing 11, and a supply of cool water may be placed in the cooling chamber 34 and in the water jacket or chamber 29 of the humidifying device (Figs. 2 and 7), by opening the inlets 33 and 28, respectively, thereto, and a supply of water or other cooling fluid medium is kept in the fluid circulating system 13—14—15—33—20 and 21.

45 The motor 16 being set in operation to drive the fluid pump 15, water is forced through the fluid circulating system 13—14—15—39—20 and 21 and passes through the cooling coil 13 wherein it is cooled by the ice or like refrigerant surrounding 50 the coil 13. The thus cooled water passes out of the cooling coil 13, by way of the pipe 21, into the cooling coil 20, and thence returns to the pump 15 by way of the pipe 39; and as the thus cooled water is circulated through the cooling coil 20, 55

- air is drawn into the extension 19 of the blower housing 18, through the inlet 38, conduit 37-36 and thence through the fresh air inlet or grille 35, and as the air is thus drawn through the conduit 37-36 it is cooled by contact with the bottom wall of the casing 11; and as the thus cooled air is drawn through the inlet 35 it is further cooled by contact with the cooling coil 20.
- The thus cooled air passes from the extension 19 of the blower housing 18, through the blower 17-18, into the air delivery duct 22, wherein it is humidified by contact with the water discharged into the duct 22, from the absorbent member 27, through the perforated jacket 31; it being noted that a supply of water is kept in the water jacket or chamber 29, wherein it is in contact with the absorbent member 27, by reason of the perforated jacket 30 surrounding the absorbent member 27.
- 20 The thus humidified and cooled air passes from the air duct 22 into the casing 11 wherein it is further cooled by contact with the cooling tank 12, and the thus cooled and humidified air passes from the housing 11, through the grille 24, from 25 which it may be delivered to a room or building.

While I have illustrated and described the preferred form of construction for carrying my invention into effect, this is capable of variation and modification, without departing from the spirit of the invention. I, therefore, do not wish to be limited to the precise details of construction set forth, but desire to avail myself of such variations and modifications as come within the scope of the appended claims.

35 Having thus described my invention what I claim as new and desire to protect by Letters Patent is:

1. An air conditioning apparatus, comprising: a casing having an air delivery grille in one wall thereof for delivering conditioned air to a room or building; a cooling tank in said casing; a blower housing having a fresh air inlet; a blower in said housing; a system for circulating a cooling fluid including a cooling coil arranged in said cooling tank and a cooling coil in the said fresh air inlet to said blower housing; means for circulating a cooling fluid through said system including a fluid pump arranged therein and a motor operating both said pump and said blower; 40 an air delivery duct extending from said blower housing into said casing and an air duct for supplying fresh air to the said fresh air inlet of said blower housing and including a portion extending exteriorly of said blower housing above the latter and in contact with a wall of said casing.

2. An air conditioning apparatus, comprising: a casing having an air delivery grille in one wall thereof for delivering conditioned air to a room or building; a cooling tank in said casing; a blower housing having a fresh air inlet; a blower in said housing; a system for circulating a cooling fluid including a cooling coil arranged in said cooling tank and a cooling coil in the said fresh air inlet to said blower housing; means for cir-

culating a cooling fluid through said system including a fluid pump arranged therein and a motor operating both said pump and said blower; an air delivery duct extending from said blower housing into said casing; a device arranged in 5 said air duct for humidifying cooled air passing therethrough and an air duct for supplying fresh air to the said fresh air inlet of said blower including a portion extending exteriorly of said blower housing above the latter and in contact 10 with the bottom wall of said casing.

3. An air conditioning apparatus, comprising: a casing having an air delivery grille in one wall thereof for delivering conditioned air to a room or building; a cooling tank in said casing; a blower 15 housing having a fresh air inlet; a blower in said housing; a system for circulating a cooling fluid including a cooling coil arranged in said cooling tank and a cooling coil in the said fresh air inlet to said blower housing; means for circulating a 20 cooling fluid through said system including a fluid pump arranged therein and a motor operating both said pump and said blower; an air delivery duct extending from said blower housing into said casing; and a device arranged in said air duct 25 for humidifying cooled air passing therethrough; said humidifying device including a water jacket surrounding said air duct and having a perforated inner wall; a perforated drum arranged in said air duct; and a water-absorbent member 30 arranged between said perforated drum and the said perforated inner wall of said water jacket.

4. An air conditioning apparatus, comprising: a casing having an air delivery grille in one wall thereof for delivering conditioned air to a room or building; a cooling tank in said casing; a blower housing having a fresh air inlet; a blower in said housing; a system for circulating a cooling fluid including a cooling coil arranged in said cooling tank and a cooling coil arranged in said fresh air 40 inlet to said blower housing; means for circulating a cooling fluid through said system including a fluid pump arranged therein; an air delivery duct extending from said blower housing into said casing and an air duct for supplying fresh 45 air to the said fresh air inlet of said blower housing including a portion extending exteriorly of said blower housing above the latter and in contact with a wall of the said casing.

5. An air conditioning apparatus, comprising: a casing having an air delivery grille in one wall thereof for delivering conditioned air to a room or building; a cooling tank in said casing; a blower housing having a fresh air inlet; a blower in said housing; a system for circulating a cooling fluid including a cooling coil arranged in said cooling tank and a cooling coil in the said fresh air inlet to said blower housing; a fresh air duct leading from the said air inlet to said blower housing and extending along said casing in contact with the bottom wall of the latter; and an air delivery duct extending from said blower housing into said casing.

WILLIAM H. LEINWEBER.
